FIG. 25

FIG.26FIG.27FIG. 1 is a rear view of the sewing machine in position of non-use;

FIG. 2 is a view of the rear face of the sewing machine in position of use;

FIG. 3 is a view of the rear face of the sewing machine, in position of use, the lower arm being exposed;

FIG. 4 is a 3/4 perspective view from the right of the front face showing the sewing machine in position of non-use;

FIG. 5 is a 3/4 perspective view from the left of the rear face of the sewing machine in position of non-use;

FIG. 6 is a 3/4 perspective view from the left of the sewing machine in position of use;

FIG. 7 is a 3/4 perspective view from the left of the rear face of the sewing machine in position of use, with lower arm exposed;

FIG. 8 is a 3/4 perspective view from the right of the rear face of the sewing machine in position of non-use;

FIG. 9 is a 3/4 perspective view from the right of the sewing machine in position of use;

FIG. 10 is a 3/4 perspective view from the right of the rear face of the sewing machine in position of use, with lower arm exposed;

FIG. 11 is a 3/4 perspective view from the left showing the front face of the sewing machine in position of non-use;

FIG. 12 shows the front face of the sewing machine in position of non-use;

FIG. 13 shows the front face of the sewing machine in position of use;

FIG. 14 is a 3/4 perspective view from the left of the front face of the sewing machine in position of use;

FIG. 15 is a 3/4 perspective view from the left of the front face of the sewing machine in position of use; the lower arm being exposed;

FIG. 16 is a side view of the sewing machine in position of non-use, showing the flywheel face;

FIG. 17 is a side view of the sewing machine in position of use, showing the flywheel face;

FIG. 18 is a side view of the sewing machine in position of use with lower arm exposed, showing the flywheel face;

FIG. 19 is a side view of the sewing machine in position of non-use showing the head side;

FIG. 20 is a side view of the sewing machine in position of use, showing the head side;

FIG. 21 is a side view of the sewing machine in position of use with lower arm exposed, showing the head side;

FIG. 22 is a plan view from above of the sewing machine in position of non-use, the handle being raised;

FIG. 23 is a plan view from above of the sewing machine in position of use, its handle being lowered;

FIG. 24 is a view from below of the sewing machine in position of non-use;

FIG. 25 is a view from below of the sewing machine in position of use;

FIG. 26 is a 3/4 perspective view from the right of the front face of the sewing machine in position of use; and

FIG. 27 is a 3/4 perspective view from the right of the front face of the sewing machine in position of use, with lower arm exposed.

I claim:

The ornamental design for a sewing machine, substantially as shown and described.
